(57) **CLAIM**

We claim the ornamental design for a cover for electronic device, as shown and described.

DESCRIPTION

FIG. 1 is a front perspective view of a cover for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the encircled portion in FIG. 7. The unshaded interior surface of the cover for electronic device shown in FIGS. 1 and 3 and the broken lines thereon form no part of the claimed design. In FIGS. 7 and 8, the broken lines encircling the portion of the claimed design illustrated in the enlargement form no part of the claimed design. All other broken lines throughout the drawing figures depict unclaimed portions and unclaimed features of the cover for electronic device.
